Frank C. Fischer
ATTORNEY

UNITED STATES PATENT OFFICE

IDA M. MARTIN, OF HILLSIDE TOWNSHIP, UNION COUNTY, NEW JERSEY

TELEPHONE-DIAL PROTECTOR

Application filed August 24, 1928. Serial No. 301,732.

The telephone now being generally adopted by telephone companies throughout the United States being of the dial type operating on automatic principles no longer affords a subscriber of the system any excuse for claiming that the operator wrongfully charged for calls which were never made; hence, even long distance as well as European calls may be charged to the subscriber of a dial telephone without redress.

It is important, as may be readily seen, that some protection be available to all subscribers of phones in the matter of insuring them against being charged for calls made by anyone but themselves or by their permission or consent; hence, an object of my invention is to provide a simple and inexpensive means of complete protection at all times to phone instruments in the absence of the subscriber thereof, to the end that it cannot be operated to obtain outside calls, yet causing no interference with the receipt of incoming calls.

Inasmuch as there are rigid rules established by all telephone companies stipulating that no attachment of any character shall be attached to their instrument which is likely to interfere or damage the same, my invention is so constructed as to preclude any possibility of affecting the telephone in any way whatsoever and even in the event of forceable removal no damage need occur to the instrument because of such removal even if violence has been employed.

The marked difference between my invention of a telephone protector and other inventions having for their object the locking up of the instrument either in part or wholly, is that in my invention less space is taken up than where the whole base is enclosed in a large box or casing, the same being cumbersome to store away when not in use, whereas my one piece protector is compact, easily slipped into position and readily disposed of in a drawer when removed from the instrument and at the same time, its cost is insignificant in comparison.

In the case where the phone dial is alone locked by a rod inserted in one of the holes in said dial, leaving the whole dial exposed

to view, the temptation thereby offered to anyone wishing to use the telephone, becomes as great as if no obstacle were present, hence an invariable attempt will be made to lift out the rod by leverage on the dial resulting in breaking of same, whereas in my invention the dial being completely covered and securely fastened to the underside of the base, a glance would at once convince anyone of the futility of an attempt to successfully remove this protector.

As will be readily seen an object of my invention is to positively limit the number of outgoing calls to the one who has to pay the monthly bill for telephone service, keeping out all others who have not been granted the privilege to use the same, in this manner affording complete security to telephone subscribers against paying for calls never made by themselves.

Another object of my invention is to provide a device that is quickly and easily applied to the automatic dial desk phone which will in no way injure, mar or interfere with the operation of said phone and which can be instantly removed whenever necessary, without giving the telephone company grounds for registering complaints.

Another advantage of my invention, arises in the fact that my device is compact, light, small, strong and durable as well as inexpensive, while it so nearly resembles the telephone instrument in finish that it is not noticeable when attached and can be moved with the instrument to any place or position without taking up additional space, just as much so as if the device were not attached, and notwithstanding its attachment no incoming calls are lost or unannounced, making it possible for anyone present to receive such messages.

While I have described in detail the construction of my invention and refer to same by reference numerals to accompanying drawing of my device, it is understood that I do not confine or restrict myself exclusively to the manner and shape of said device but reserve to myself the right to change or modify the construction, shape or material used in said device in any manner or form as

shall be within the scope of my invention.

The accompanying drawings illustrate the salient features of my invention.

Figure 1 is an end view of the device applied to a dial telephone.

Figure 2 is a cross sectional view of the device applied to a dial telephone.

Figure 3 is a plan view showing the application of the device.

Figure 4 is a perspective view of the device.

Figure 5 is a plan view of a blank from which the device may be formed.

Referring to the drawing, an automatic telephone having a handle 6 and a dial 7, is shown to have the device applied thereto for the purpose of preventing unauthorized use of the telephone. The device comprises a sheet metal casing 8 having a horizontal lip 9 to engage the base 10' of the telephone. A top plate 10 covers the dial of the telephone and integral down-turned flanges 12 prevent access from the sides to the dial. Top plate 10 is angularly bent upward at 13 and is provided with a pair of forks 14 and 15 which embrace the handle portion of the telephone. Fork 14 has pivoted thereto a bar 16, the latter being provided with an aperture at one end adapted to register with an aperture 17 in the fork 15.

In Figure 5 is shown a blank of fairly heavy sheet metal from which the device may be formed. The blank is bent along the dotted lines 18 and 19 to form the horizontal lip 9 and the top plate 10. The blank is also cut along the lines 20 to enable the flanges 12 to be bent along the lines 21. The inclined portion 13 and the fork 14 are properly positioned by bending along the lines 22 and 23.

In application, the device is placed over the dial of an automatic telephone so that the flanges 12 embrace the sides of the dial 7 and the lip 9 engages the base of the telephone.

The forks 14 and 15 embrace the handle of the telephone and a lock 24 securely holds the bar 16 to the fork 15 so that unauthorized use of the telephone is prevented.

From the above description it will be seen that there has been provided a simple and effective device for preventing unauthorized use of automatic telephones, which device, at the same time, does not affect the normal operation of the telephone mechanism.

Although the foregoing is descriptive of the preferred embodiment of the invention, it will be apparent that minor changes may be made in its construction, without the exercise of invention or conflicting with the scope of the claims hereto appended.

Having thus described my invention, what I claim as new and desire to secure by Letters Patent, is:—

1. A device for preventing unauthorized use of a dial telephone, comprising a casing having a lip adapted to engage the base of the telephone and a top plate to cover a dial

on the telephone, down-extending flanges integral with the top plate and adapted to embrace the sides of the dial, and forks integral with the top plate adapted to embrace the handle portion of the telephone, said forks being provided with means to receive a lock to prevent removal of the device.

2. In combination with a dial telephone, a casing having a lip engaging the base of the telephone and a top plate to cover the dial, down-extending flanges integral with the top plate and embracing the sides of the dial, and means for locking the casing on the handle of the telephone to prevent removal of the casing from the dial.

3. In combination with a dial telephone, a casing embracing the top and sides of the dial, a lip integral with the casing to engage the base of the telephone, and means for locking the casing on the handle of the telephone to prevent unauthorized removal of the casing from the dial.

4. In combination with a dial telephone, a casing comprising a lip engaging the base of the telephone, a top plate positioned over the dial of the telephone, down-extending flanges integral with the top plate and embracing the sides of the dial, a pair of forks integral with the top plate and embracing the handle of the telephone, and a bar pivoted to one of the forks, said bar having an aperture at one end adapted to register with an aperture in the other fork to receive a lock to prevent unauthorized removal of the casing from the dial.

5. In combination with a dial telephone, a casing having a lip engaging the base of the telephone and a top plate to cover the dial, down-extending flanges integral with the top plate and embracing the sides of the dial, and means for locking the casing on the telephone to prevent removal of the casing from the dial.

6. In combination with a dial telephone, a casing embracing the top and sides of the dial, a lip integral with the casing to engage the base of the telephone, and means for locking the casing on the telephone to prevent unauthorized removal of the casing from the dial.

This specification signed this 23rd day of August, 1928.

IDA M. MARTIN.
